UNITED STATES PATENT OFFICE.

JOSEPH T. CURTIS, OF NEW YORK, N. Y.

HAT AND METHOD OF MAKING THE SAME.

Application filed October 17, 1927. Serial No. 226,658.

My invention relates to hats and the method of making the same and has for its object to provide an improvement in ladies' hats or toques.

5 Heretofore it has usually been the custom to form the close fitting hats or toques so much in vogue in recent years, from a number of pieces of material fitted together and stitched in shape, each finished model being a certain 10 size.

My improved device consists in the novel arrangement of fabric or other material so as to do away with such intricate patterns, my hat being formed approximately from a single 15 piece of fabric and at the same time is self-fitting and easily and quickly adjusted to conform to the head and neckline of the wearer, and when in place, makes an attractive hat of the draped style, which may be 20 made of various materials to suit the individual taste.

In the drawings illustrating this invention, like characters of reference designate similar parts throughout the several views.

25 Referring to the drawings:

Figure 1 represents the blank cut from the material of which the hat is to be made:

Figure 2 shows the blank folded ready to be secured together:

30 Figure 3 is a cross section on line $x-x$ of Figure 2.

Figure 4 shows the completed hat as worn on the head of a person.

The blank or body of the hat 1 is cut from the 35 fabric in rectangular shape, which is then folded with the side edges meeting together. The closed edge of the body is then cut in a circular line from the point 5 to the point 9, as illustrated in Figure 2.

40 Having now cut the material in the desired shape, the open edges 6 and 7 of the shaped material are secured together by stitching or other suitable means.

45 A band 8 of fabric or other suitable material is secured to the inside of the lower edge of the hat and may be reinforced at 10 if

desired by any suitable stiffening material to prevent the lower edge of the hat from stretching out of shape.

After the pieces forming the body portion 50 of the hat have been secured together and turned, a loop or tab 3 of the same or contrasting material is secured to the lower outside edge of the hat, adjacent the vertical seam as indicated at 11, one end of this loop being 55 secured near one side of the seam and the other end being secured at a greater distance to the opposite side of the seam, the end of the loop nearest the seam lying at an angle of about 45° with respect to the bottom of the 60 hat, as illustrated in Figure 4.

By drawing the top of the hat or toque, at 9, through the loop or tab 3, the hat is adjusted to fit the head of the wearer, and by this simple adjustment of the hat, all surplus 65 space in the top of the device is disposed of and it then becomes unnecessary to pull the hat so far down upon the head as to render it uncomfortable, which is frequently the case with the styles in small hats already on the 70 market.

While I have specified a certain shape of hat and have illustrated the adjusting loop in a certain position, I do not desire to be limited to those particular illustrations of my 75 device as these details may be changed without departing from the spirit of my invention.

Having thus described my invention, what I claim as new and desire to protect by Letters Patent, is:

A head covering cut in a single piece from material to form the body portion of the hat when folded together, means for securing the top and side edges thereof, and a loop 85 attached to the lower edge of the body of the head covering through which the top of said head covering is drawn to regulate the height of said head covering.

In witness whereof I have signed my name 90 this 7th day of October, 1927.

JOSEPH T. CURTIS.
